(57) **CLAIM**

The ornamental design for a bodysuit, as shown and described.

DESCRIPTION

FIG. 1.1 is a front view of a bodysuit with fastener in open position showing my new design; and

FIG. 1.2 is a front view of a bodysuit with fastener in closed position of my new design.

The elements of the bodysuit illustrated in dashed lines in particular which exist outside the dash dot dash in Fig. 1.2 are for the purpose of illustrating portions of the article that form no part of the claimed design. The dash dot dash line illustrates boundaries of the claimed design. The dash lines that fall within the boundaries of the claim are small portions of the bodysuit that form no part of the claimed design.
